CLAIM

The ornamental design for telephone line surge protection assembly, as shown and described.

DESCRIPTION

FIG. 1 is a front elevational view of a telephone line protector assembly showing my new design, the adjacent modules and the mounting plate being omitted for clarity of illustration;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front and upper right perspective view thereof;

FIG. 8 is a front and upper right perspective view of the complete telephone line surge protection assembly;

FIG. 9 is a front elevational view thereof;

FIG. 10 is a back elevational view thereof;

FIG. 11 is a left side elevational view thereof;

FIG. 12 is a right side elevational view thereof;

FIG. 13 is a top plan view thereof; and,

FIG. 14 is a bottom plan view thereof.
